CARBONATOR

James Kantor, Chicago, Ill., assignor to The
Liquid Carbonic Corporation, Chicago, Ill., a
corporation of Delaware

Application May 7, 1941, Serial No. 392,265

1 Claim. (Cl. 261—36)

The present invention relates to apparatus for impregnating water, such as that used in carbonated beverages, with CO₂.

One of the objects of the invention is to provide a carbonator which, with a comparatively small water container, may impregnate a comparatively large amount of water in a relatively short period of time. To this end, in the present invention, I provide a container in which a large volume of CO₂, commonly referred to as gas, is maintained, preferably under pressure, and the water to be carbonated is delivered within this container in the presence of the gas, in a fine spray. In passing through the gas, this fine spray of water will absorb a large proportion of gas. This initially carbonated water is again re-circulated through a sprayer which delivers the water a second time in the form of a fine spray, the water passing through the gas, thereby absorbing the gas a second time, so that eventually it has absorbed about all of the gas it can take up.

For the purpose of disclosing my invention, I have illustrated an embodiment thereof in the accompanying drawings, in which:

Fig. 1 is a side elevation of carbonator embodying my invention, portions thereof being shown in section;

Fig. 2 is a plan view of the connection casting for the container;

Fig. 3 is a side elevation thereof;

Fig. 4 is a plan view of the container, with the top removed; and

Fig. 5 is a detail section of one of the spray heads.

In the embodiment of the invention illustrated, I provide a base 1 on which the various parts of the carbonator are adapted to be mounted. This base is provided with a hollow supporting standard 2 having a top 3 on which is supported the cylindrical container 4. This container rests on a bottom closure plate 5 and is secured to the standard 2 through the medium of cap screws 6 passing through a ring 7 on the container 4 and into the standard. A suitable packing ring is interposed between the bottom edge of the container cylinder 4 and the bottom plate. The top of the container is closed by a cover 8 secured to the container through the medium of bolts 9 passing through the cover and through a clamping ring 10 on the cylinder 4. A suitable packing ring is interposed between the top edge of the cylinder and the cover plate 8 to insure a tight packing. This container has arranged therein a plurality, preferably four in number, of spray

heads which are disposed at the top of the cylinder 4. Two of these spray heads 11 and 12 which may be referred to as the initial spray heads are mounted at the tops of a pair of branch supply pipes 13, one for each spray head, which terminate in a coupling 14 secured to the top of the inlet pipe 15.

The secondary spray heads 16 and 17 are secured at the ends of delivery pipes 18 and 19. 10 The spray heads are all tied together through the instrumentality of a suitable spider 20 which maintains them in their spaced relationship and tends to hold the heads more or less rigidly in position.

15 On the underside of the bottom plate 5, I mount a connecting unit 21 which is preferably in the form of a single casting provided on its top surface with an annular flange 22 to provide a recessed surface into which a suitable packing may be fitted. This casting is provided with bolt-receiving openings 23 adapted to receive securing bolts 24 passing through the bottom plate 5 and into the openings, whereby the casting will be secured to the under face of the plate 5, surrounding an opening, corresponding in general in contour, to the casting. This casting is provided with an inlet extension 25 screwthreaded at its bottom to receive an elbow 26 into which is screwthreaded the infeed pipe 15. This infeed pipe 15 is connected by a suitable conduit or pipe 27, through the medium of the elbow 27' and a conduit 28 with a reciprocating pump 29 mounted on the base 1 which has an intake opening 30 connected with the source of water supply, whereby, the water

35 to be carbonated may be delivered by this pump to the cylinder 4 through the primary spray heads 11 and 12.

30 The inlet extension 25 communicates with a coupling 31 secured on the top of the casting 21 and this coupling is provided with branches receiving, respectively, the threaded ends of pipes 32 and 33 connected, respectively, through the medium of suitable elbows, with the secondary spray pipes 18 and 19 leading to the secondary spray heads 16 and 17. This extension 25 is provided with an inlet opening 34 connected by a suitable coupling 35 to the discharge side of a centrifugal pump 36 likewise mounted upon the base 1. The intake side of this centrifugal pump is connected by a suitable conduit 37 to an outlet 38 opening into the bottom of the cylinder 4. This outlet 38, as shown in Figs. 2 and 3, is adapted to have connected thereto the pipe coupling or conduit 37, so that, as the water flows through the outlet opening 38, it will discharge into the

40 45 50 55

40 The inlet extension 25 communicates with a coupling 31 secured on the top of the casting 21 and this coupling is provided with branches receiving, respectively, the threaded ends of pipes 32 and 33 connected, respectively, through the medium of suitable elbows, with the secondary spray pipes 18 and 19 leading to the secondary spray heads 16 and 17. This extension 25 is provided with an inlet opening 34 connected by a suitable coupling 35 to the discharge side of a centrifugal pump 36 likewise mounted upon the base 1. The intake side of this centrifugal pump is connected by a suitable conduit 37 to an outlet 38 opening into the bottom of the cylinder 4. This outlet 38, as shown in Figs. 2 and 3, is adapted to have connected thereto the pipe coupling or conduit 37, so that, as the water flows through the outlet opening 38, it will discharge into the

centrifugal pump and by said pump will be again discharged into the container.

This pump 36 is driven by a belt drive 36' from a drive wheel 39 mounted on a shaft 39', which shaft is driven by the same motor driving shaft 40 operating the piston rod 40' of the reciprocating double acting pump 29.

The fitting 21 is provided with a gas inlet 41 having an inlet opening 42 into which is secured the gas inlet pipe 43 which extends upwardly in the cylinder 4 having a reverse bend 44, so that the gas or CO₂ will be discharged into the cylinder near the top. The gas inlet 41 is connected with a suitable CO₂ supply, in any desired manner, and preferably the gas is maintained in the cylinder 4 under pressure.

The fitting 21 is also provided with an air discharge opening 45 having secured therein an air escape pipe 46. This pipe extends to the top of the cylinder 4 and is provided with an escape head 47 arranged over a baffle plate 48. Preferably, this air discharge outlet 45 is connected by a suitable conduit or pipe 49, with the water inlet check valve on the discharge side of the reciprocating pump, so that as this valve is operated, a snift valve in the conduit 49 is opened to permit discharge of air from the cylinder to atmosphere.

A water discharge outlet 50 is also provided in the fitting 21 and this discharge outlet is connected through a suitable valve with the discharge fitting or discharge pipe of the carbonator.

In operation, the water, through the medium of the reciprocating pump 29, is drawn from the source of supply and delivered through the pipe 15 and the two branches 13, to the spray heads 16 and 17. By these spray heads, the water is broken up into an extremely fine spray and in this sprayed form, falls through the atmosphere of CO₂ contained in the container 4. As a result of the breaking up of the water in this extremely fine spray, considerable of the air is released from the water and, at the same time, the water absorbs a large quantity of CO₂ in the container 4. This water, which is fairly well permeated with gas by the time it reaches the bottom of the

container, then flows through the discharge 38 into the centrifugal pump 36 which again delivers the water through the fitting 25 to the two secondary supply pipes 18 and 19 and through the secondary spray heads 16 and 17. The water is thus again broken up into a fine spray and this fine spray, in falling through the atmosphere of CO₂ contained in the container 4, the water completely absorbs the CO₂ so that it is fully saturated. This saturated water, of course, may be drawn off from time to time, as needed, through the discharge opening 50.

In Fig. 5, I have illustrated a detail section of one of the discharge heads. As each of the heads is of the same construction, only one is sufficient. This head comprises a hollow base 51 connected by a coupling member 52 with its pipe and this base, on its interior, has a lug 53 adapted to receive a stem 54 upwardly extending. Surrounding this stem is a coiled spring 55 which rests on the lug 53. A cap 56 covers the top of this spring and this cap is adjusted through the medium of suitable set screws 58 so that the spring may be compressed to the desired degree to thereby vary the size of the spray openings formed between the coils of the springs.

I claim as my invention:

In a carbonator, in combination, a base, a well formed in said base, an upwardly extending supply pipe secured in the bottom of said well, a spray head mounted on the upper end of said pipe, a T-coupling mounted on the top of said well, a pair of upwardly extending re-circulating pipes extending from said T-coupling, spray heads mounted on the upper end of said T-coupling, a CO₂ inlet in said base, an upwardly extending CO₂ supply pipe connected with said inlet, an air discharge outlet in said base, an upwardly extending air discharge pipe connected to said discharge outlet, a supply pump adapted for connection with the water supply connection with the bottom end of said supply pipe, a re-circulating pump having its inlet connected with the discharge opening in said base and its outlet connected with the bottom of said well, and a casing enclosing said pipes.

JAMES KANTOR.
